INK BOTTLE

Filed May 16, 1932

ATTORNEYS

UNITED STATES PATENT OFFICE

BONNER B. HAUSER, OF DENVER, COLORADO

INK BOTTLE

Application filed May 16, 1932. Serial No. 611,582.

This invention relates to ink bottles, its primary object being to provide a bottle having means for measuring ink contained therein, in a segregated quantity to facilitate the filling of pen-points or fountain pens in a convenient and cleanly manner.

Still further objects are to be found in details of construction and a novel arrangement of parts, as will be fully brought out in the course of the following description.

In the accompanying drawing, in the several views of which like parts are similarly designated,

Figure 1 is a vertical sectional elevation of the bottle,

Figure 2, a partially broken elevation of the bottle in the position for filling the measuring means from the contents of the bottle,

Figure 3 is an elevation of the measuring element of the bottle, removed therefrom,

Figure 4 is a section on the line 4-4, Figure 1,

Figure 5 is a partially sectional top view of the bottle,

Figure 6 is a partially sectional elevation, showing a modification in the construction of the closure,

Figure 7 is a sectional elevation of a bottle of modified form,

Figure 8 is a top view of the bottle shown in Figure 7,

Figure 9 is a sectional elevation of a measuring element of modified form,

Figure 10 is a cross-section along the line 10-10, Figure 9, and

Figure 11 is a sectional elevation of another modification of the measuring element.

Referring further to the drawing, the bottle 5, as shown in Figures 1 and 2, has an externally screw-threaded neck 6 for the application of a correspondingly threaded cap 7, preferably made of hard rubber. The edge of the neck is beveled, as at 8, and the cap has interiorly a soft-rubber gasket 9 to engage with the beveled edge. The gasket may be

made integral with the hard-rubber body part of the cap, or it may be made separate from the body part and set in an interior recess of the same, as shown at 10, in Figures 6 and 7. An air space around the gasket 9 provides for its expansion.

The cap has in its top surface, a groove 12 of dove-tail section for the application of a piece of felt or other suitable material 13, adapted for wiping surplus ink from the pen after it has been filled with ink from the bottle, and it is desirable that the wiper be removable from the cap so that it can be removed when saturated with the ink.

Inasmuch as the bottle is inverted in order to fill the measuring-element hereinafter to be described, it is necessary that it be formed to provide a firm hold for the hand of the user. To this end, the bottle shown in Figures 1 and 2 has an external groove 14 and that of Figures 7 and 8 has flattened sides 15.

The neck of the bottle has, interiorly, a groove 16 for the application of the measuring element now to be described.

The measuring element is to some extent, similar to that shown in my United States Patent No. 1,852,520, issued April 5, 1932.

It consists of a container 17 of cylindrical form having a pointed bottom portion, and integrally connecting at its upper end with an entrance chamber 18 of larger diameter. The chamber has a plurality of circumferential ports 19, through which ink may enter, and above the open upper end of the container is a rest 20 for a pen holder whose nib is inserted in the container.

The measuring element is preferably made of an elastic material, such as rubber, and it has at the upper end of its entrance chamber a rim 21 which fits within the internal groove 16 of the neck of the bottle and thus suspends the element within the same.

In order to fill the container with a measured quantity of ink from the contents of the bottle, the latter is inverted, as illus-

trated in Figure 2, thereby permitting the ink to enter the chamber 18 through the ports 19 whence it flows into the container 17, after the bottle has been replaced in an upright 5 position. The cap 7 may then be removed and the nib of a pen inserted in the container. The shoulder of the holder for the nib or pen engages the rest 20 so that only the nib comes in contact with the ink. In this manner soiling or wetting of the end of the holder is prevented.

In the form shown in Figure 1, the rest for the pen holder is provided by an extension 15 22 of the wall of the container, inside the entrance chamber, said extension projecting to or slightly above the lower ends of the ports 19 so that the pen holder engaging the rest will always be above ink in the container and the chamber. The extension has circumferential openings 23 for draining the contents 20 of the chamber into the container.

The form of the measuring element, shown in Figure 11, differs from the other in that the extension which provides the rest for the 25 pen holder is provided by a separate tubular piece 24 inserted into the container.

In the modification illustrated in Figures 9 and 10, the rest is provided by upwardly projecting, spaced lugs 25 extending from the 30 sloping bottom 26 of the chamber to or slightly above the lower ends of the ports 19. The measuring element is applied to the bottle by springing its elastic rim into the groove of the neck of the same. In this position, it 35 closes the neck of the bottle and when the latter is inverted the ink will flow into the element through the ports of its entrance chamber.

The fluid-tight closure between the cap 40 and the end of the neck prevents the escape of any ink passing into the space above the measuring element.

After the container has been filled and the bottle is again in an upright position, a fountain pen is filled by removing the cap and then inserting the nib of the pen into the container. The latter is proportioned to contain the 45 amount necessary for filling an ordinary fountain pen, and owing to the presence and the position of the rest, the pen may be filled 50 without soiling or wetting the end of its holder.

Any surplus ink may be removed from the pen or pen holder on the wiper 13, and when 55 the latter becomes saturated, it is readily removed and replaced by another.

It will be understood that any surplus ink within the neck portion of the bottle, after the latter has been restored to its upright position, will flow from the chamber 18 through the ports 19 into the bottle, so that the measuring element will only contain the ink that passed into the container 17.

It will also be understood that while the 60 device as shown and described, is particularly

adapted for use as an ink bottle, it may be employed to dispense different liquids, such as those used for medicinal purposes.

The form of the measuring element shown in Figure 11 has the advantage of a limited adjustment of the rest to vary the position of its end relative to the ports 19. 70

Other minor changes in the construction of the bottle and its measuring element may be made within the spirit and scope of the invention. 75

What I claim and desire to secure by Letters Patent is:

1. An ink bottle comprising a vessel, and a measuring element suspended therein and composed of an entrance chamber having ports for the admission of ink, a container of reduced diameter at the bottom of the chamber, and a rest for a pen holder projecting upwardly from said bottom to adjacent 80 said ports, and including passages for the flow of ink from said bottom to the container. 85

2. An ink bottle comprising a vessel, and a measuring element suspended therein and composed of an entrance chamber having ports for the admission of ink above an inwardly sloping bottom, a container of reduced diameter at the bottom of the chamber, and a rest for a pen holder projecting 90 upwardly from said bottom to adjacent said ports, and including passages for the flow of ink from said bottom to the container. 95

3. An ink bottle comprising a vessel, and a measuring element suspended therein and composed of an entrance chamber having ports for the admission of ink, a container of reduced diameter at the bottom of the chamber, and a rest for a pen holder projecting upwardly from said bottom to adjacent 100 said ports, and having ports for the flow of ink from the chamber to the container. 105

4. An ink bottle comprising a vessel, and a measuring element suspended therein and composed of an entrance chamber having ports for the admission of ink, a container of reduced diameter at the bottom of the chamber, and a rest for a pen holder composed of a tubular extension of the container, projecting upwardly from said bottom to adjacent 110 said ports, and having ports for the flow of ink from the chamber to the container. 115

5. An ink bottle comprising a vessel, and a measuring element suspended therein and composed of an entrance chamber having ports for the admission of ink, a container of reduced diameter at the bottom of the chamber, and a rest for a pen holder, composed of a tube inserted in the container and projecting upwardly therefrom to adjacent 120 said ports, the tube having ports for the flow of ink from the chamber to the container. 125

6. An ink bottle comprising a vessel, and a measuring element suspended therein and composed of an entrance chamber having ports for the admission of ink, a container 5 of reduced diameter at the bottom of the chamber, and a rest for a pen holder composed of a tube vertically adjustably inserted in the container and projecting upwardly therefrom to adjacent said ports, the tube 10 having ports for the flow of ink from the chamber to the container.

In testimony whereof I hereunto affix my signature.

BONNER B. HAUSER.
